UNITED STATES PATENT OFFICE.

KARL AUGUST BRÄUNING, OF ZAANDAM, NETHERLANDS.

AUTOMATIC FIREARM.

1,350,543.

Specification of Letters Patent. Patented Aug. 24, 1920.

Application filed July 10, 1919. Serial No. 309,918.

To all whom it may concern:

Be it known that I, KARL AUGUST BRÄUNING, engineer, a subject of Germany, and resident of Zaandam, Netherlands, have invented 5 certain new and useful Improvements in Automatic Firearms; and I do hereby declare the following to be a full, clear, and exact description of the invention, such as will enable others skilled in the art to which 10 it appertains to make and use the same, reference being had to the accompanying drawing, and to letters or figures of reference marked therein, which form a part of this specification.

15 This invention relates to fire arms, and more particularly to fire arms of the type shown and described in my prior United States Letters Patent, No. 1,070,579, issued August 19, 1913, in which the breech bolt 20 carries a pair of locking levers operated by projections formed on the slide, the arrangement being such that during the rearward movement of the slide those projections force the locking levers inward and thereby 25 disconnect the bolt from the barrel; whereas during the return or forward movement of the slide, the aforesaid levers are forced outward into position to again lock the bolt and barrel together. Reference may be had to 30 this patent, which is hereby made a part of the present specification, for a further understanding of the action of the locking levers and directly associated parts.

The present invention expressly comprises 35 certain improvements in or relating to the mechanism disclosed in my said patent as will be hereinafter fully explained; the essential object of the invention, stated briefly, being the provision of a device which, when 40 actuated, serves to retract the slide and, in consequence, effect the loosening of the empty cartridge and the disengagement of the locking levers. The rearward movement of the slide is effected by hand in ordinary 45 firing, and requires considerable effort; whereas the operating device which I now provide, is extremely simple in its construction and can be easily and quickly actuated.

An embodiment of the invention is illustrated in the accompanying drawing, in which:

Figure 1 is a fragmental side elevation of a gun equipped with the improved slide-operating device, showing the parts, in normal position with the breech closed;

Fig. 2 is a plan view of Fig. 1 with parts broken away and in section;

Fig. 3 is a vertical section on line 3—3 of Fig. 2; and

Fig. 4 is a view similar to Fig. 3, but showing the breech partly open.

Referring more particularly to the drawing, 1 indicates the slide which is mounted on the fixed breech frame 2 and is shown in Figs. 1, 2 and 3 as at the limit of its forward movement, *i. e.*, in normal position. To effect the rearward movement of the slide, there is provided a substantially L-shaped lever 3, the inner arm 4 of which is in the form of a circular plate or block and 65 is rotatably fitted in a circular recess or socket 5 formed in the rear portion of the slide. This arm or block 4 is notched to provide a nose or shoulder 6 for coöperation with an upstanding abutment or lug 7 70 formed on the adjacent portion of the breech frame 2, so that when lever 3 is swung in the direction indicated by the arrow X (Fig. 1) by means of its knob or handle 8, the block 4 will rotate in its socket and its shoulder 6 75 will be pressed forcibly against said lug or abutment 7 with the result that the slide is shifted rearwardly into the position represented in Fig. 4. The long outer arm of the 80 lever stands at that time in vertical position, having been stopped in such position by striking against a projection 12 formed on the exterior wall of the socket 5. Thereafter, during the continued rearward movement of the lever, the slide is forced backward by direct traction so as to open the 85 breech completely.

As the slide moves rearward, the two projections or noses 9 formed on its opposite sides act to force the locking levers 10 carried by the breech bolt 15 inward in the manner disclosed in my above-identified prior patent, thereby releasing or unlocking the breech bolt from the barrel, while at the same time the bolt itself is slightly retracted and, in turn, loosens the empty cartridge 11 in the barrel. The locking levers, however, form no part of the present invention which is limited to the provision of the operating element 3 and its connection 95 with the slide; and for that reason it is deemed unnecessary in this case to illustrate and describe their construction and mounting with any degree of particularity, especially in view of their inclusion in the 100 105 110

patented structure. For all present purposes, therefore, the mere statement as to the employment of said levers is sufficient.

During the subsequent closing of the breech, the action of the recoil spring upon the breech bolt restores the operating lever 3 to normal or Fig. 1 position, in which a projection 13 on the free end of the outer arm of said lever rests upon the horizontal face 14 of the slide. A small spring may be utilized to assist the return movement of the lever; but since this spring is not essential to the invention, it has not been illustrated. The locking levers 10 are reengaged with 15 the barrel to lock the breech bolt thereto, during the return movement of the slide, as explained in said patent.

It will be noted that the handle 8 of the operating lever 3 may be pulled in a backward direction to open the breech without turning said lever relatively to the slide, it being only necessary therefor that the axis

of said handle shall be lower than the axis of the inner arm 4 about which the lever rotates.

25

What I claim is:

In an automatic firearm of the kind described, a fixed breech frame, a breech bolt, locking members arranged on said breech bolt, a slide movable on the breech frame 30 adapted to act on the locking members and to open the breech, a fixed abutment on the fixed breech frame, and a lever pivotally mounted on said slide the longer arm of which is provided with an actuating knob 35 while the shorter arm is applied against the aforesaid abutment of the fixed breech frame.

In testimony whereof I affix my signature in presence of two witnesses.

KARL AUGUST BRAUNING.

Witnesses:

JAFFYSTRA WESAR,
FRITZ KUPFER.
